UNITED STATES PATENT OFFICE.

GEORGE AINSWORTH, OF GREAT NECK, NEW YORK, ASSIGNOR TO ALFRED VESTER SONS, INC., OF PROVIDENCE, RHODE ISLAND, A CORPORATION OF RHODE ISLAND.

DESIGN FOR A COMBINATION SOCKET COVER AND HUSK FOR LIGHTING FIXTURE.

Application filed February 26, 1923. Serial No. 5,269. Term of patent 14 years.

To all whom it may concern:

Be it known that I, GEORGE AINSWORTH, a citizen of the United States, and residing at Great Neck, in the county of Nassau and State of New York, have invented a new, original, and ornamental Design for a Combination Socket Cover and Husk for Lighting Fixture, of which the following is a specification, reference being had to the accompanying drawing, forming a part thereof.

Figure 1 is a side view of a combination socket cover and husk for lighting fixture, showing my new design.

Figure 2 is a bottom plan view of same.

I claim:

The ornamental design for a combination socket cover and husk for lighting fixture, as shown.

GEORGE AINSWORTH.
